CLAIM

The ornamental design for a trainer for martial arts, as shown and described.

DESCRIPTION

FIG. 1 is a perspective view of a trainer for martial arts showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof;

FIG. 8 is a perspective view showing an exemplification of the trainer for martial arts in use; and,

FIG. 9 is a perspective view showing another exemplification of the trainer for martial arts in use.

The broken lines illustrate environmental structure which forms no part of the claimed design.
